COMBINED BATTERY CHARGER AND CONVERTER

Charles R. Moore, P.O. Box 2602,
South Bend, Ind. 46613

Filed Apr. 10, 1969, Ser. No. 16,658

Term of patent 14 years

Int. Cl. D13—02

U.S. Cl. D26—15

Fig. 1

Fig. 2

Fig. 4

Fig. 3

FIG. 1 is a perspective view of a combined battery charger and converter embodying the present design;

FIG. 2 is a top plan view;

FIG. 3 is a side elevational view; and

FIG. 4 is an end elevational view.

The side and end opposite those shown in FIGS. 3 and 4 are the same as those shown in the respective figures.

I claim:

The ornamental design for a combined battery charger and converter, substantially as shown and described.
